FUEL INJECTION PUMP MOUNTING

Herbert H. Haas, Royal Oak, Mich., assignor, by mesne assignments, to Continental Motors Corporation, Muskegon, Mich., a corporation of Virginia

Application June 18, 1956, Serial No. 591,901

8 Claims. (Cl. 123—195)

This invention relates to fuel injection type internal combustion engines, and more particularly to a mounting means for a plurality of fuel injection pumps carried on the engine crankcase.

In the construction of engines utilizing a plurality of fuel injection pumps, it has heretofore been the practice to mount the pumps separately on the engine. Thus, synchronization and adjustment of the pumps had to be accomplished after assembly on the engine, entailing considerable difficulty on the part of assemblers and maintenance personnel. In addition, removal of injection pumps often involves removal or disassembly of other associated or interfering equipment.

An object of my invention is to facilitate assembly of accessories on an engine by constructing a unitary mount for a plurality of accessories on which accessories may be bench assembled and adjusted, and provided with means for aligning the accessories with their associated drives during assembly on the engine.

A further object of my invention is to facilitate assembly and maintenance of fuel injection pumps on fuel injection engines by providing a unitary mount for a plurality of pumps which may be readily removed from the engine with the pumps attached for accomplishing bench testing and adjustment.

Another object of the invention is to provide a simplified engine assembly by constructing a fuel injection pump accessory mounting which does not interfere with other accessories upon removal and installation.

For a more complete understanding of the present invention, reference may be had to the accompanying drawings illustrating a preferred embodiment of the invention in which like characters refer to like parts throughout the several views and in which

Fig. 1 is an elevational end view, partially cut away, of a preferred V-type internal combustion engine incorporating the invention.

Fig. 2 is a diagrammatic cross-section, primarily showing the accessory portion of the engine taken substantially on the line 2—2 of Fig. 1.

Fig. 3 is an enlarged fragmentary view of the fuel injection pump and mounting bracket shown in Fig. 2.

Fig. 4 is a cross section taken substantially on the line 4—4 of Fig. 3.

Fig. 5 is an end view of the mounting bracket as seen from the line 5—5 of Fig. 3, and

Fig. 6 is an end view of the bracket as seen from the line 6—6 of Fig. 3.

Fig. 7 is a cross-section taken substantially on the line 7—7 of Fig. 2.

Referring to Fig. 1, a fuel injection V-type internal combustion engine 10 is illustrated as having a crankcase structure 11 provided with a substantially flat upper mounting surface 11a and inclined side surfaces 11b to which banks of cylinders 12 are secured. The upper surface 11a is the mounting base for an accessory gear housing 13 and the various engine accessories, such as

2

blower fan assemblies 14 and fuel injection pump assemblies 15.

All the accessories are adapted to be operated through an accessory drive shaft assembly 16 as shown in Fig. 2. At one end of the drive shaft assembly 16 is a driven gear 17 which extends through a slot 18 in the crankcase structure 11 and is drivingly meshed with a drive gear 19 preferably secured to the flywheel end of a crankshaft 20. The accessory drive shaft assembly 16 preferably comprises a centrally longitudinally disposed shaft 21 overlying the crankcase upper surface 11a and extending parallel to the axis of the crankshaft 20. The shaft 21 is directly drivingly connected to the blower fan assemblies 14 and any other desired accessories, and is provided with a driving gear 22 operably engaged with a pair of fuel injection pump driven gears 23, as shown in Fig. 7. The driven gears 23 are secured to fuel injection pump drive shafts 24 which are connected to the fuel injection pumps 15 through shaft coupler assemblies 25 of conventional construction permitting the pumps 15 to be readily disconnected from the drive shafts 24.

Figs. 3 through 6 illustrate the fuel injection pump mounting to the crankcase. A mounting bracket structure 30 having inclined pump mounting faces 31 and foot members 32 is adapted to straddle the shaft 21 and to be secured to raised bosses 33 provided on the crankcase upper surface 11a by stud bolts 34 or other suitable means.

The fuel pumps 15 are secured to the mounting faces 31 by bolts 35 or other means, and are preferably held in accurate longitudinal and lateral alignment with respect to each other by an upwardly turned flange member 36 provided at one end of the bracket structure 30 and by a plurality of dowel pins 37 protruding from the mounting faces 31 and inserted in matching holes provided in the base of the pumps 15.

The pumps 15 may thus be bench adjusted and synchronized while secured to the mounting bracket structure 30, after which the bracket structure is secured in place on the crankcase 11. In order to achieve accurate alignment of the pumps 15 with their respective couplers 25, lugs or dowels 40 are secured to the bosses 33 by bolts 41 or other means. The lugs coat with mating shoulders 42 provided on the inner portions of the bracket legs 32 when the bracket structure 30 is moved in place toward the couplers 25, effecting an automatic alignment. This arrangement permits quick assembly of the pumps on the crankcase in a space which is normally generally inaccessible, and also eliminates the necessity for adjusting and synchronizing pumps after installation on the engine.

Also, it will be seen that the legs of the bracket provide a tunnel for the shaft 21, which is not disturbed by the removal and installation of the pumps. In fact, removal and installation of the pumps is achieved without removing or handling the other engine equipment, with the possible exception of the fan members 14a of the blower assemblies 14.

Although I have described but one embodiment of the present invention, it will be apparent to one skilled in the art to which the invention pertains that various changes and modifications may be made therein without departing from the spirit of the invention or the scope of the appended claims.

I claim:

1. In an internal combustion engine having an accessory mounting surface, accessory driving means, a plurality of accessories at least two of which are adapted to be synchronized and each of which has a driven element adapted for engagement with said driving means, and a mounting means for said synchronized accessories and

adapted to be removably secured to said mounting surface, and a dowel coating with said mounting means and said mounting surface to locate and guide said mounting means for accurately aligning said driven elements with respect to said driving means as the assembled mounting means and accessories are being installed on said engine.

2. In a fuel injection type internal combustion engine having a crankcase provided with an accessory mounting surface, accessory driving means supported by said engine and overlying said crankcase mounting surface, said accessory driving means comprising a plurality of injection pump driving means, a plurality of fuel injection pumps each having a driven element adapted to be removably engaged respectively with said injection pump driving means, and a pump mounting bracket adapted to be removably secured to said crankcase mounting surface, said pumps mounted on said bracket, and means coating with said bracket and said crankcase to accurately align said pump driven elements with respect to said pump driving means as the assembled bracket and pumps are being installed on said crankcase.

3. In a fuel injection type internal combustion engine having a crankcase provided with an accessory mounting surface, accessory driving means supported by said engine and overlying said crankcase mounting surface, said accessory driving means comprising a plurality of rotatable shafts, a plurality of fuel injection pumps each having a driven element adapted to be removably engaged respectively with one of said shafts, and a pump mounting bracket adapted to be removably secured to said crankcase mounting surface and to straddle another of said shafts, said pumps mounted on said bracket, and means coating with said bracket and said crankcase to accurately align said pump driven elements with respect to said first shafts as the assembled bracket and pumps are being installed on said crankcase.

4. In a fuel injection type internal combustion engine having a crankcase provided with an accessory mounting surface, accessory driving means supported by said engine and overlying said crankcase mounting surface, said accessory driving means comprising a plurality of injection pump driving means, a plurality of fuel injection pumps each having a driven element adapted to be removably engaged respectively with said injection pump driving means, and a pump mounting bracket adapted to be removably secured to said crankcase mounting surface, said pumps mounted on said bracket, and means coating with said bracket and said crankcase to accurately align said pump driven elements with respect to said pump driving means as the assembled bracket and pumps are being installed on said crankcase, said crankcase mounting surface provided with raised bosses, and said bracket having feet disposed to rest on said bosses, means securing said feet to said bosses, and said aligning means comprising dowel members laterally adjustably secured to said crankcase mounting surface and adapted to contact said bracket feet.

5. In an internal combustion engine having an accessory mounting surface, accessory driving means, a plurality of accessories at least two of which are adapted to

be synchronized and each of which has a driven element adapted for engagement with said driving means, an integral support having symmetrically arranged inclined upper accessory mounting faces, means whereby both said synchronized accessories can be respectively secured to said inclined faces, and means removably securing said support to the accessory mounting surface of said engine.

6. In an internal combustion engine having an accessory mounting surface, accessory driving means, a plurality of accessories at least two of which are adapted to be synchronized and each of which has a driven element adapted for engagement with said driving means, an integral support having symmetrically arranged inclined upper accessory mounting faces, means whereby both said synchronized accessories can be respectively secured to said inclined faces, and means removably securing said support to the accessory mounting surface of said engine, said support having a longitudinally extending tunnel, said accessory driving means having a drive shaft extending through said tunnel and drivingly connected to other accessories.

7. In an internal combustion engine having an accessory mounting surface, accessory driving means, a plurality of accessories at least two of which are adapted to be synchronized, said synchronized accessories each having a driven element carried thereby, a mounting structure removably secured to said mounting surface, said synchronized accessories secured to said mounting structure, said driven elements arranged for independent adjustment when said assembled mounting structure and synchronized accessories are removed from said mounting surface and aligned for synchronized engagement with said driving means only when said assembled mounting structure and synchronized accessories are secured to said mounting surface.

8. In an internal combustion engine having an accessory mounting surface, accessory driving means, a plurality of accessories at least two of which are adapted to be synchronized, said synchronized accessories each having a driven element carried thereby, a mounting structure removably secured to said mounting surface, said synchronized accessories secured to said mounting structure, said driven element arranged for independent adjustment when said assembled mounting structure and synchronized accessories are removed from said mounting surface and aligned for synchronized engagement with said driving means only when said assembled mounting structure and synchronized accessories are secured to said mounting surface, and a dowel coating with said mounting structure and said mounting surface to locate and guide said mounting means for accurately aligning said driven elements with respect to said driving means as said mounting structure is positioned for securing same to said mounting surface.
